Albert Vaicekauckas,

INVENTOR

BY *Victor J. Evans*

ATTORNEY

UNITED STATES PATENT OFFICE

ALBERT VAICEKAUCKAS, OF ROCKFORD, ILLINOIS

LOCK

Application filed December 14, 1928. Serial No. 325,963.

This invention relates to a keyless lock of the mortice type, the general object of the invention being to provide means whereby the dead bolt can only be manipulated from one side of the door or barrier, thus making it impossible to manipulate said bolt from the other side of the door, thereby providing a burglar-proof lock.

A further object of the invention is to make the parts adjustable so that the lock manipulating means can be placed on either side of the door and also to make the latch bolt slideable on the dead bolt so that both bolts work in one hole formed in the lock casing and the striker plate.

A still further object of the invention is to provide a rotatable member having a handle thereon, mounted on a part of the knob stem, for manipulating the dead bolt, and to provide a dog for locking the dead bolt in either retracted or projected position.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an edge view of portion of a door, showing the improved lock applied thereto.

Figure 2 is a face view of a portion of the door, showing the locking plate.

Figure 3 is a section on line 3—3 of Figure 1.

Figure 4 is a section on line 4—4 of Figure 3.

Figure 5 is a section on line 5—5 of Figure 3.

Figure 6 is a section on line 6—6 of Figure 3.

Figure 7 is a view similar to Figure 3, but showing both bolts projected.

Figure 8 is a view of the sleeve and its handle for manipulating the dead bolt.

Figure 9 is a view of the sectional member for operating both bolts from the knob stem and the sleeve.

Figure 10 is a perspective view of the dead bolt.

Figure 11 is a perspective view of the latch bolt, showing the parts thereof separated.

Figure 12 is a view of the striker plate.

In these drawings, the numeral 1 indicates the casing of the lock which is morticed in the door A in the usual manner, said casing including a cover plate 2 and the front plate 3 which is countersunk in the edge of the door and which is formed with a single opening 4 for the latch bolt 5 and the dead bolt 6. The latch bolt is formed with the grooves 7 in its outer part, one of which receives the guiding rib 8 on the outer part of the dead bolt and the other receives a projection 9 formed on the top wall of the opening 4. The latch bolt is formed with a central opening 10 into which extends a projection 11 formed on the casing and a spring 12 is arranged in said opening and bears against the projection and the front wall of said opening and acts to hold the latch bolt projected. The forked part 5' of the latch bolt is fastened to the front part thereof by the screw 5'' so that this forked part can be reversed, whereby the lock can be used either as a left hand lock or a right hand lock, thus enabling the dead bolt manipulating means to be placed on either side of the door.

The lugs on the ends of the prongs of the forked part are engaged by the projections 13 on the member 14 through which the stem 15 of the knobs or handles 16 pass so that by partly rotating the knobs or handles, this member 14 will be rocked to retract the latch bolt in the usual manner. This member 14 has a reduced part fitting in a circular hole in the cover plate of the casing and the reduced part on the other face of said member 14 fits in a rounded recess in a ring member 17 which has a reduced part fitting in a circular hole in the casing, the opening in the ring part being made of larger diameter than the knob stem so that the stem can pass therethrough and be rocked without moving said member 17. The reduced part of this mem-

ber 17 is formed with the oppositely arranged openings 18 and a sleeve 19 is rotatably mounted on a part of the stem and extends through the escutcheon plate 20 on one face of the door and through a part of the door and has oppositely arranged ears 21 on its inner end which enter the notches 18 so that when this sleeve is turned, the member 17 will also be turned.

10 A handle 22 has a ring shaped part 23 encircling the outer end of the sleeve and a set screw 24 passes through the part 23 into any one of a number of notches 25 formed in the sleeve whereby the handle can be adjusted on 15 the sleeve to permit the lock to be placed on doors of different thicknesses.

As will be seen, by applying pressure to the handle 22, the sleeve will be turned to move the member 17 and this sleeve is turned independently of the knob stem 15 and the knob stem can be turned without moving the sleeve.

An arm 26 is connected with the member 17 and carries a pin 27 which passes through 25 a slot 28 formed in the rear part of the dead bolt so that the rocking movement of the member 17 will retract and project the dead bolt. This dead bolt is guided in its movement by means of a projection 29 formed on 30 the casing engaging a slot 30 in the dead bolt. A dog 31 is pivotally arranged in the casing and has a projection 32 thereon for engaging either one of a pair of notches 34 formed in the rear part of the dead bolt so that the 35 dog will lock the dead bolt in either its projected or retracted positions.

A spring 35 presses the dog toward the dead bolt and the free end of the dog is formed with a rounded enlargement 31' 40 which engages the pin 27 on the arm of the member 17 in such a manner that when the member 17 is turned, the pressure of the pin against the rounded enlargement will cause the dog to move outwardly against the action 45 of its spring and thus move the projection on the dog out of the notch 34 which it engages. After the bolt has been moved to a certain extent by the turning of the member 17, the pressure of the spring on the dog will 50 cause the rounded part of the dog to complete the movement of the bolt.

The detachable knob 16 is threaded to the stem 15 and the parts are locked together by the set screw 16' and the striker plate 36 has 55 a single opening 37 therein to receive both bolts, the upper wall of the opening having a projection 38 thereon for entering the top groove 7 of the latch bolt.

From the foregoing it will be seen that 60 the latch bolt can be manipulated in the ordinary manner from either side of the door through means of the handles or knobs 16, but the dead bolt can only be manipulated from one side of the door by turning the 65 handle 22 to cause the sleeve 19 to rock the

member 17 so that the pin 27 on the arm 26 of said member will move the dead bolt, after having first moved the locking dog into releasing position. Thus it is impossible for a person to open the door from one side after 70 the dead bolt has been projected by the handle 22 on the opposite side, as there is no way in which the dead bolt can be reached from that side of the door which is opposite the side on which the dead bolt manipulating 75 means are placed.

As before stated, by making the latch bolt in two portions which are detachably connected together, the forked part can be reversed so that the dead bolt manipulating 80 means may be placed on either side of the door.

It is thought from the foregoing description that the advantages and novel features of the invention will be readily apparent.

It is to be understood that changes may be made in the construction and in the combination and arrangement of the several parts, provided that such changes fall within the 90 scope of the appended claims.

What I claim is:—

1. A lock of the class described comprising a casing, a spring actuated latch bolt slidably arranged in the casing, a dead bolt slidably arranged in the casing, a spring actuated locking dog in the casing for positively locking the dead bolt in either projected or retracted position, a stem passing through the casing, handles on the ends of the stem, a member movable with the stem for contracting the latch bolt, a manually operated member rotatably mounted on the stem, an arm carrying member rotatably arranged in the casing and actuated by said manually operated member, a pin on the arm engaging a 95 part of the dead bolt for projecting and retracting the same, said pin also moving the locking dog to releasing position.

2. A lock of the class described comprising a casing, a spring actuated latch bolt slidably arranged in the casing, a dead bolt slidably arranged in the casing, a spring actuated locking dog in the casing for locking the dead bolt in either projected or retracted position, a stem passing through the casing, handles 110 on the ends of the stem, a member movable with the stem for contracting the latch bolt, a manually operated member rotatably mounted on the stem, an arm carrying member rotatably arranged in the casing and actuated by said manually operated member, a pin on the arm engaging a part of the dead bolt for projecting and retracting the same, 115 said pin also moving the locking dog to releasing position, said latch bolt being formed of two parts which are detachably connected together whereby the parts can be reversed so that the dead bolt manipulating means can be placed on either side of a door.

3. A lock of the class described comprising 120

ing a casing, a latch bolt and dead bolt slidably arranged in the casing, a stem passing through the casing, handles connected with the ends of the stem, spring means for normally holding the latch bolt projected, means associated with the stem for retracting the latch bolt, said dead bolt having a slot therein and a pair of notches therein, an arm carrying member rotatably arranged on the stem, 5 a pin on the arm extending through the slot in the dead bolt, a sleeve rotatably arranged on a part of the stem and engaging the arm carrying member whereby said member will be turned when the sleeve is turned, a handle 10 member adjustable longitudinally on the sleeve, a spring actuated locking dog having a projection thereon for engaging either one of the notches in the dead bolt, said dog having a rounded part engaging the pin 15 whereby the dog will be moved to releasing position when the member carrying the pin is moved.

4. A lock of the class described comprising a casing having an opening therein, a 20 projection on one wall thereof, a latch bolt and dead bolt slidably arranged in the casing and having their outer ends arranged in the opening, one of the bolts having grooves therein and the other having a rib thereon engaging one of the grooves, the other groove 25 being engaged by the projection, a stem passing through the casing, handles on the ends of the stem, means associated with the stem for manipulating the latch bolt, a member rotatably mounted on one part of the stem, a handle 30 connected with said member and means operated by said member for manipulating the dead bolt.

In testimony whereof I affix my signature.
